his attorney

UNITED STATES PATENT OFFICE.

JOHN H. HARTMAN, OF LANCASTER, PENNSYLVANIA, ASSIGNOR TO THE HUBLEY MANUFACTURING CO., OF LANCASTER, PENNSYLVANIA, A CORPORATION OF PENNSYLVANIA.

TOY REFRIGERATOR.

Application filed March 6, 1925. Serial No. 13,643.

This invention relates to toys, and more particularly to a toy constructed in imitation of an ordinary refrigerator containing a glass block in imitation of ice and small food platters for the amusement of children.

The invention will first be hereinafter more particularly described, with reference to the accompanying drawings, which are 10 to be taken as a part of this specification, and then pointed out in the claims at the end of the description.

In said drawings, Fig. 1 is a front elevation of a toy refrigerator embodying my 15 invention; the door on the right hand side thereof being open to show the interior construction;

Fig. 2 is a side elevation of the same;

Fig. 3 is a transverse section;

20 Fig. 4 is a vertical section taken on the line 4—4 of Fig. 3; and

Fig. 5 is a fragmentary detail view illustrating a hinge construction for securing 25 swinging doors to the body of the device without using ordinary hinges.

Referring to said drawings, in which the same reference characters are used to denote corresponding parts in different views, the two sides and back of the device are 30 formed by a single sheet metal plate A, preferably steel, while another sheet metal plate B, also preferably of steel, forms the bottom and inner side wall of an imitation ice box in the left hand side of the device 35 and to said wall is riveted or bolted a third sheet metal plate C of substantially U-shaped form, to provide small imitation food compartments or shelves in the right hand side of the device, and these parts are 40 assembled and secured together by means of a top plate D and a bottom plate D¹ connected and held together by means of tie-bolts F which are inserted through apertures in said bottom plate and have threaded 45 ends which are screwed into hollow interiorly threaded lugs or bosses d on the underside of the top plate; a cast metal front E having door openings therein and marginal flanges e, which overlap the sides 50 of the plate A and aid in holding the as-

sembled parts together, being also clamped between said top and bottom by means of said tie-bolts. The front plate has two door openings on the left hand side thereof and a single door opening on the other side 55 which extends nearly the full height of the device, and each of these openings is closed by a swinging door. The larger door on the right hand side is denoted by the letter I, and the smaller doors by the letters K and K¹. Each door has formed integrally therewith hooks of the form shown in Fig. 5 of the drawings which are adapted to engage openings in the upright side portions of said front plate, one near the upper edge 60 and the other near the lower edge of the door, so as to form an interlocking hinge-connection between the door and said front plate composed entirely of integral parts thereof without extraneous parts or ordinary hinges. The hooks on the door I, which are denoted by the letters i and i¹, are bent in a reverse direction to the hooks on the doors K and K¹ which are denoted by the letters k and k¹. Said hooks are 65 each formed with a double bend, the intermediate portion of which extends rearwardly substantially at right angles to the base and to the free end of the hook and in a plane substantially parallel with the front 70 and rear sides of the door; the free end of the upper hook extending upwardly in a plane substantially parallel with said sides while the free end of the lower hook extends inwardly in a plane substantially at right angles to said sides and substantially parallel with the base. The described hinge connection renders it impossible for one of the doors to be disconnected or removed accidentally or otherwise when in either open 75 or closed position. In order to attach the door it is necessary to raise the lower end thereof sufficiently to bring the pintle on its upper end in a substantially horizontal plane, for insertion in the opening in the 80 upper part of the front plate and then swing the door into partially closed position, so as to permit the pintle on the lower end thereof to be inserted in the opening 85 at the lower end of the front plate, and 90

thereupon the door may be swung back and forth on its hinges without danger of becoming disconnected or removed by pulling upon it when in either open or closed position, and to remove the door it must first be brought into partially open position, when the pintle on the lower end thereof may be withdrawn from the opening at the lower end of the front plate, and then the lower end of the door must be raised into position to permit the pintle at the upper end thereof to be withdrawn from the opening at the upper end of the front plate.

I thus provide a toy constructed in imitation of a refrigerator and consisting of a few simple and inexpensive parts adapted to be easily assembled and secured together so as to form a strong and durable device of the character referred to, which is not liable to get out of order or to be taken apart by a child, and which will afford amusement and pleasure especially to little children who are fond of toys made in imitation of household articles with which they are familiar.

In order to produce a more realistic effect giving the appearance of a miniature refrigerator having an ice box and upper and lower food compartments containing ice and edibles, a block of glass may be placed in the ice box, as at X, while small platters P, in imitation of platters of food, are placed on the shelves in the food compartments beside the ice box.

While I have shown a toy refrigerator having in the front plate thereof three door openings each provided with a swinging door, it will be understood of course that the number of doors may be increased or diminished as desired, and various changes may be made in the details of construction and arrangement of parts without departing from the spirit and scope of my invention.

Having thus described my invention, what I claim as new and desire to secure by Letters Patent of the United States is:

1. A toy refrigerator consisting of a metal front plate having a plurality of door openings therein, each provided with a swinging door, a cast metal top and bottom, and a plurality of sheet metal plates between said top and bottom arranged to form therewith interior compartments in imitation of the usual food compartments and ice box of an ordinary refrigerator; one of said sheet metal plates being shaped to form the back and two sides of the refrigerator, another forming the bottom and inner side wall of an imitation ice box located above a lower simulated food compartment, and another being of substantially U-shaped form and having its bottom secured to said side wall of said imitation ice box, so as to form small imitation food

compartments or shelves beside said ice box located above the larger lower food compartment, and tie bolts connecting said top and bottom so as to clamp the assembled sheet metal plates and front therebetween and hold them in assembled relation.

2. A toy refrigerator composed of cast metal front, top and bottom and sheet metal parts assembled and secured together so as to simulate a refrigerator having a lower large food compartment, upper small food compartments at one side and an ice box on the other side; said front plate having a plurality of door openings therein on one side and a single door opening on the other side thereof each provided with a hinged door; said parts being assembled and secured together by tie-bolts connecting said top and bottom.

3. A toy refrigerator constructed of sheet metal parts and cast metal top and bottom together forming a lower compartment and a superposed imitation ice box at one side and shelves on the other side forming the bottoms of small food compartments beside said ice box and a cast metal front having openings therein each provided with a swinging door; said parts being assembled and held together by tie-bolts connecting said top and bottom plates between which the assembled parts are clamped by said bolts; said doors having hooks formed integral therewith, each hook having an intermediate portion extending beyond the rear edge of the door in a plane substantially parallel therewith while the base and free ends of the hook extend substantially at right angles to said intermediate portion, the free end of the lower hook extending inwardly from the inner side of the door substantially at right angles thereto and approximately parallel with the base of the hook, and the free end of the upper hook extending upwardly substantially at right angles to the intermediate portion thereof in a plane substantially parallel with said door; said front plate having holes formed therein in which said hooks are inserted so as to provide a hinge-connection between the door and front plate by integral interlocking parts thereof.

4. In a device of the character described, a hinge-connection for a swinging door consisting of upper and lower hooks projecting from the rear inner side of the door substantially at right angles thereto, each hook having an intermediate portion which extends beyond the rear edge of the door in a plane substantially parallel therewith, the base and free end of the hook extending substantially at right angles to said intermediate portion and the free end of the lower hook extending inwardly in a substantially horizontal plane substantially at right angles to said intermediate portion

and said door while the free end of the upper hook extends upwardly substantially at right angles to said intermediate portion and substantially parallel with said door,

5 and a door-plate having openings therein adapted to receive said hooks and forming therewith an interlocking hinge-connection

composed of integral parts of the door and door-plate, whereby the door cannot be removed when in either open or closed position. 10

In testimony whereof I affix my signature.

JOHN H. HARTMAN.
